US00D910940S

(12) United States Design Patent (10) Patent No.: US D910,940 S
(45) Date of Patent: * Feb. 16, 2021

(54) WASHING MACHINE

(71) Applicant: LG ELECTRONICS INC., Seoul
(KR)

(72) Inventors: Nerry Son, Seoul (KR); Byeongkook Kim, Seoul (KR); Hyerim An, Seoul (KR); Junghwan Lee, Seoul (KR)

(73) Assignee: LG ELECTRONICS INC., Seoul
(KR)

() Term: 15 Years

(21) Appl. No.: 35/508,300

(22) Filed: Jul. 9, 2019

(80) Hague Agreement Data

Int. Filing Date: Jul. 9, 2019

Int. Reg. No.: DM/204035

Int. Reg. Date: Jul. 9, 2019

Int. Reg. Pub. Date: Jan. 10, 2020
